UNITED STATES PATENT OFFICE.

ERNEST O. SEITZ, OF DETROIT, MICHIGAN, ASSIGNOR TO C. M. HALL LAMP COMPANY,
OF DETROIT, MICHIGAN, A CORPORATION OF MICHIGAN.

HEADLIGHT ATTACHMENT.

Application filed August 28, 1922. Serial No. 584,675.

To all whom it may concern:

Be it known that I, ERNEST O. SEITZ, a citizen of the United States of America, residing at Detroit, in the county of Wayne and State of Michigan, have invented certain new and useful Improvements in Headlight Attachments, of which the following is a specification, reference being had thereto in the accompanying drawings.

10 This invention relates to lamps and particularly to improvements in lamps designed for use on motor vehicles, traction cars, boats and the like.

15 An object of the invention is to provide a movable reflector for the lamp which may be easily and readily adjusted to an inclined position.

20 Another object is to provide simple and effective means for adjusting the reflector.

Another object is to provide neat and compact means for inclosing a portion of the operating means and also limiting the movement of the latter.

25 Another object is to provide auxiliary means for adjusting the reflector relative to the lamp casing independently of the main adjusting means.

Another object is to provide a strong and durable construction which can be manufactured at a comparatively low cost.

30 With the above and other objects in view the invention consists in certain novel features of construction combination and arrangement of parts as will be more fully described and particularly pointed out in the appended claims.

In the accompanying drawing:

Figure 1 is a side elevation of a lamp embodying my invention and showing parts in section;

Figure 2 is a top plan view of the plate showing the cover of the housing removed and showing a fragmentary sectional view of the reflector;

Figure 3 is a detail sectional view taken on the line 3—3 of Figure 1;

Figure 4 is a perspective view of the cover for the housing;

Figure 5 is a perspective view of the housing showing the parts located therein.

50 Referring now to the drawing in which like characters of reference designate corresponding parts throughout the several views, the numeral 1 designates a lamp casing hav-

ing the usual glass face 2 which is carried 55 in a frame 3 removably secured to the casing.

A pair of headed pivot members 4 are removably secured to the lamp casing at diametrically opposite points thereof and extend inwardly therefrom. A reflector 5, preferably of parabolic form, is located within the casing and is provided with an inclined annular flange 6 which is removably secured to a pair of brackets 7 pivotally mounted upon the headed members 4. An incandescent bulb or illuminating member 9 is positioned at the focal point of the reflector and is detachably connected to an adjustable holder 10 extending through the reflector.

A plate 11 is removably secured to the lamp casing as shown at 12 and is provided with a tubular portion 13 which extends through an opening 14 in the lamp casing 75 and surrounds an electric cord 15 which has an electrical connection with the bulb 9. A housing 16 is formed integral with the plate 11 upon one side of the tubular portion 13 and is provided with a curved portion as 80 shown at 17. The housing is provided further with an elongated extension 18 which has an opening 19 formed therein in registration with an elongated opening 20 in the lamp casing. A plurality of aligned spaced 85 lugs 21 extend inwardly from the ends of the housing and engage opposite sides of a channelled annular member 22 and a deeper curved portion 22' is provided to house the annular member 22. The upper edges of 90 the housing are provided with grooves 23 which are in alignment with the extension 18. A reciprocatory arm 24 extends through the annular member and is mounted in the grooves 23. A cylindrical enlargement 95 25 is formed on the arm 24 and is adapted to move through the annular member 22 and abut the sides of the housing. The cylindrical enlargement 25 is provided with beveled portions 26 at its opposite ends 100 to facilitate the passage thereof through the annular member. A coil spring 27 is located in the channelled portion of said annular member and surrounds the arm 24 and tightly fits the beveled portions 26 thereby 105 preventing a voluntary movement of said enlarged portion 25 through the annular member 22.

A pin 28 is pivotally mounted in aligned openings 29 formed in a pair of spaced parallel lugs 30 extending at right angles from one end of the arm 24 and is provided with a transverse threaded opening 31 which engages a threaded portion 32 of a rod 33. A bracket 34, removably secured to the inclined flange 6 of the reflector, surrounds the rod 33 and is provided with an annular seat 35 which receives the grooved head 36 thereof. The inclined flange 6 is provided with an opening 37 which registers with the head of the rod. Any suitable tool may be inserted through the opening 37 to engage the grooved head for rotating the rod 33 and adjusting the reflector independently of the operation of the arm 24.

A washer 38 surrounds the rod 33 and abuts the lugs 30 while a coil spring 38' surrounds the rod between the washer 38 and the bracket 34 and securely holds said bracket against the head of said rod thereby preventing rattling.

The arm 24 is provided at its opposite end with an angular extension 39 which projects through the aligned openings 19 and 20 in the extension 18 and lamp casing respectively and is connected to suitable operating means (not shown) extending within convenient reach of the operator.

A cover 40 is removably secured to the housing 16 and cooperates therewith to enclose the annular member 22 and a portion of the arm 24 including the cylindrical enlargement 25. The cover 40 is provided with a transversely extending longitudinally curved slot 41 which receives the cylindrical enlargement 25. A curved groove 42 is formed in the curved slot of the cover intermediate the ends of the slot and receives the annular member 22. A pair of aligned grooves 43 are formed in the edges of the cover and receive the operating arm 24. The cover is also provided with an elongated extension 44 which registers with the extension 18 of the housing and receives a portion of the arm 24.

A second housing 45, corresponding in construction to the housing 16, is formed integral with the plate 11 upon the opposite side of the tubular portion 13 and may be used to house the operating mechanism to move the reflector when it is not convenient to use the housing 16. A cover plate 46 is secured to the second housing while not in use.

Movement of the arm 24 in one direction will cause the reflector 5 to be moved to a downwardly inclined position, whereupon movement of the arm in the opposite direction will return the reflector to normal position. The reflector may be adjusted independently of the movement of the arm 24 by rotating the rod 33.

While it is believed that from the

foregoing description the nature and advantages of the invention will be readily apparent, I desire to have it understood that I do not limit myself to what is herein shown and described and that such changes 70 may be resorted to when desired as fall within the scope of what is claimed.

What I claim as my invention is:

1. The combination with a lamp casing, of a reflector in said casing, an arm operably connected to said reflector for moving the same, a housing secured to said casing, and means in said housing surrounding said arm for resisting movement of said arm. 75

2. The combination with a lamp casing, 80 of a reflector in said casing, a reciprocatory arm operably connected to said reflector for moving the same, a housing secured to said casing, and means in said housing surrounding said arm for resisting movement of said 85 arm in either direction.

3. The combination with a lamp casing, of a reflector in said casing, a reciprocatory arm operably connected to said reflector for moving the same, a housing secured to said 90 casing, an annular enlargement formed on the said arm and located in said housing, and means in said housing engageable with said enlargement for resisting movement of said arm, the end walls of said housing 95 limiting the movement of said enlargement in either direction.

4. The combination with a lamp casing, of a reflector in said casing, an arm operably connected to said reflector for moving the 100 same, a housing secured to said casing, a stationary annular member in said housing surrounding said arm, and means seated within said annular member for resisting movement of said arm. 105

5. The combination with a lamp casing, of a reflector in said casing, an arm operably connected to said reflector for moving the same, a housing secured to said casing, a stationary annular member in said housing 110 surrounding said arm, an enlargement formed on said arm movable through said annular member, and a spring in said annular member engageable with said enlargement for resisting movement of said arm. 115

6. The combination with a lamp casing, of a reflector in said casing, an arm operably connected to said reflector for moving the same, a housing secured to said casing, an annular member in said housing surrounding said arm, projections extending from said housing and engaging opposite sides of said annular member, and spring means in said annular member for resisting movement of said arm. 120

7. The combination with a lamp casing, of a reflector in said casing, a housing secured to said casing with openings therein, an arm extending through said openings and operably connected to said 130

reflector for moving the same, and an enlargement formed on said arm and located in said housing to limit the movement of said arm through said openings.

5 8. The combination with a lamp casing, of a reflector mounted in said casing, an arm operably connected to said reflector, a

housing within said casing and secured thereto, an annular member in said housing surrounding said arm, and a grooved cover 10 secured to said housing and cooperating therewith to retain said annular member and to limit the movement of said arm.

ERNEST O. SEITZ.
